CLAIM

The ornamental design for a video game controller, as shown and described herein.

DESCRIPTION

FIG. 1 is a top, front perspective view of a video game controller, showing our new design;

FIG. 2 is a bottom, rear perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof; and,

FIG. 8 is a left side elevation view thereof.

The broken lines shown are included for the purpose of illustrating portions of the video game controller that form no part of the claim.

1 Claim, 4 Drawing Sheets
